UNITED STATES PATENT OFFICE

LOYD H. BOATTENHAMER, OF OKLAHOMA CITY, OKLAHOMA

DESIGN FOR A CRACKER CONTAINER

Application filed March 31, 1930. Serial No. 35,071. Term of patent 3½ years.

To all whom it may concern:

Be it known that I, LOYD H. BOATTENHAMER, a citizen of the United States, residing at Oklahoma City, in the county of Oklahoma and State of Oklahoma, have invented a new, original, and ornamental Design for Cracker Container, of which the following is a specification, reference being had to the accompanying drawing, forming part thereof,

Fig. 2 is an end elevational view of the container.

I claim:

The ornamental design for a cracker container, as shown.

LOYD H. BOATTENHAMER.
